UNITED STATES PATENT OFFICE

GEORGE D. KRATZ, OF AKRON, AND EMIL SCHNEDAREK, OF CUYAHOGA FALLS, OHIO,
ASSIGNORS TO THE FALLS RUBBER COMPANY, OF CUYAHOGA FALLS, OHIO, A COR-
PORATION OF OHIO

DESIGN FOR A TIRE

Application filed November 9, 1928. Serial No. 28,819. Term of patent 14 years.

To all whom it may concern:

Be it known that we, GEORGE D. KRATZ and EMIL SCHNEDAREK, citizens of the United States, residing, respectively, at Akron and at Cuyahoga Falls, in the county of Summit and State of Ohio, have invented a new, original, and ornamental Design for a Tire, of which the following is a specification, reference being made to the accompanying drawing, forming a part thereof.

The drawing is a perspective view of a tire showing our new design, the novel ornamentation being the same on both sides.

We claim:

The ornamental design for a tire as shown and described.

GEORGE D. KRATZ.
EMIL SCHNEDAREK.
